(57) **CLAIM**

The ornamental design for the cutting blade, as shown and described.

DESCRIPTION

FIG. 1 is a perspective view of a cutting blade, according to the present design;

FIG. 2 is a back view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is an enlarged perspective view of box 8 shown in FIG. 1;

FIG. 9 is an enlarged rear view of box 9 shown in FIG. 2; and,

FIG. 10 is an enlarged front view of box 10 shown in FIG. 3.

The broken lines are for the purpose of showing environmental structure and form no part of the claimed design.

1 Claim, 9 Drawing Sheets
